UNITED STATES PATENT OFFICE.

THOMAS ROBERTSON, OF TORONTO, ONTARIO, CANADA.

LOZENGE-MACHINE.

SPECIFICATION forming part of Letters Patent No. 257,615, dated May 9, 1882.

Application filed October 26, 1880. (No model.) Patented in England April 19, 1880.

To all whom it may concern:

Be it known that I, THOMAS ROBERTSON, of the city of Toronto, in the county of York, in the Province of Ontario, Canada, have invented 5 certain new and useful Improvements in Lozenge-Machines, of which the following is a specification.

This invention has relation to the manufacture of plain, printed, and embossed lozenges 10 by machinery in such manner that the lozenge material enters the machine in the form of a sheet of lozenge-paste at one end and passes out at the other end of the machine as finished goods ready for drying, the several operations 15 of cutting, embossing, and printing the lozenges being performed in succession by means of automatically-acting machinery working in unison with conveying apparatus, as more particularly described hereinafter.

20 Referring to the accompanying drawings, Figure 1 is a side-view, in two parts, of a machine, in the construction of which my improvements are embodied. In this figure the cam-wheel is shown in section to show the channels. Fig. 1^a is a detail view, showing the means for rotating the printing-head. Figs. 2, 25 3, and 4 are sections on the lines *a b*, *c d*, and *e f*, respectively. Fig. 4^a is an enlarged detail end view of the printing-head shaft and spring 30 locking-block. Figs. 5, 6, and 7 are details of the cutting apparatus on an enlarged scale. Fig. 8 is a detail plan view of the lozenge-conveying apparatus. Fig. 9 is a detail view of the gearing for operating the apron and the 35 lozenge-receiving tray, and Fig. 10 is a sectional detail view of the cutting apparatus and the apron and cutter-block-carrying frame.

Some portions of the machine are substantially the same as described and claimed by 40 me in a previous patent, No. 185,698, dated December 26, 1876, notably the lozenge-conveying mechanism and driving-gear, and need not therefore be again set forth in detail.

The principal portion of the present invention relates to the arrangement of the apron, cutting-block, and cutting apparatus, as more clearly shown in Fig. 10 of the drawings.

A is the frame of machine, constructed preferably of cast-iron in the form shown, and consisting of two open sides connected by rails and bolts.

B is the driving-shaft; B', the driving-pulley; B² B³, the driving-gear of machine; B⁴, the hand and fly wheel; and C, the machine-shaft, to each end of which are fastened the 55 channelled cam-wheels C' C'. These wheels are provided with two channels, C² C³, forming cams, which, as the wheels revolve, cause rollers placed therein to rise and fall with a stroke of definite extent and character, imparting motion to and governing the action of the operating parts, to which the rollers connect.

D is the cutter-block, placed at the front end of a frame, D', which is hinged to the main frame at *d*. This frame is connected by the 65 roller D² to the inner channel, C³, of the master-wheels, and has communicated to it, as the cam-wheels revolve, a reciprocating up and down motion on the fulcrum *d* as a center. This frame is counterbalanced by a weight on 70 its arm D³, and is provided with adjusting-screws *d'* for the purpose of regulating the stroke to a nicety in relation to the cutting-head E. This head E is stationary, and is held in the jaws of the brackets E' on the 75 frame A by screws *e*.

F are the lozenge-cutters, fastened to the under side of the head, with the upper edge of their tubular base on a level with the face of the conveyer-table G. The lozenge-conveyer 80 table and conveyer-bars are of substantially the same construction as that illustrated in my said patent of December 26, 1876, with the exception that ridges G' are provided for the purpose of arresting the momentum of the lozenges at the end of each stroke, in order that 85 they may be left in accurate position.

Another improvement consists of finger-bars G², which act with a drawing motion in substitution for the push-bars hitherto used. These 90 finger-bars are attached to a cross-head, are bent downwardly at their front end, and pass through the spur-stems of the cutters, drawing the lozenges (which are forced up after they pass through) out of the cutter upon the table 95 within the stroke of the next succeeding conveyer-bar.

H (see Fig. 7) are the cutter-guards, which relieve the cutters from the lozenge-paste.

The reciprocating hinged frame D' is provided with a feed-apron, I, which is worked 100 with an intermittent motion toward the cut-

ters or rollers from an eccentric, I', (see Fig. 9,) on the machine shaft, and rod, lever, and ratchet-wheel connection. The apron I is used both as a feeding and a cutting apron, as it is stretched over and around a roller journaled in the frame D', immediately in front of the cutter-block, interposing itself as a moving cutting-surface between the cutter-block proper and the cutters.

10 As will be clearly seen in Fig. 10 of the drawings, the apron I passes around two rollers journaled in the pivoted frame D', and it therefore reciprocates vertically with the cutter-block D, and in close contact therewith 15 when the frame D' is operated.

J is the embossing-head, worked with a reciprocating up-and-down motion in unison with the movement of the lozenges from the channel C² of the master-wheel by the roller, rocking-lever, and rod connection, as shown. The embossing-block J' on the head is made detachable, and is hinged so that it may be turned up for inspection when desired without detaching it from its fastenings. The face of the embossing-block is recessed at regular intervals to correspond with the position of the lozenges and the design to be produced.

K is the printing-head, consisting of a rotary cross-bar, K', to which are attached four (more or less) printing-blocks, K². These blocks are made adjustable on their supports, and are provided with compression-springs k, which act as a cushion and compress when the printing-blocks are in contact with the lozenges. 35 The printing-head is operated with an intermittent up-and-down motion over the conveyer-table, by means of the rods, pivoted lever, and roller connection, to the channel C² of the cam-wheel shown, and with an intermittent rotary motion by means of the pivoted hook L on the conveyer-frame and the sprocket-wheel L'. The hook L, engaging with the arm of the sprocket-wheel at each forward stroke of the conveyor-frame draws the printing-head around on the return-stroke of the conveyer-piece one-quarter of a revolution, thus changing the printing-block at each stroke and presenting a new printing-face. The printing-head is secured in position after each movement by a spring locking-block, M, (see Fig. 4^a,) which bears on the respective faces of the block M', secured to the cross-bar k' of the printing-head as the said shaft is turned, each printing-block having a corresponding face on the block M'.

N is the inking-roller, and N' the ink-distributing rollers. These rollers are supported in bearings upon a bracket, N², which is in turn supported by standards N³, bolted to 60 the cross-head O of the conveyer-frame. Thus the inking-roller has communicated to it a reciprocating motion to and from the printing-head, which is rotated to present the edges of the printing-blocks in succession each time 65 the roller is brought forward. As the roller recedes, a pawl, P, pivoted on the stationary

portion of the frame engages with a ratchet-wheel on the end of the roller-shaft and turns the roller around one or more teeth, or a sufficient distance to present a freshly-inked surface to the printing-block on the next forward stroke.

Q is the lozenge-receiving tray working on slide-bars placed underneath the conveyer-table on the main frame, and fed forward in 75 unison with the delivery of the lozenges at the end of the conveyer-frame. Motion is imparted to the receiving-tray from a toothed wheel, which is fastened to a shaft having a ratchet-wheel connection with a rod, I², from 80 the eccentric I'.

R is a scrap-apron, which receives the scrap from the slide R', and carries it out of the machine, delivering it into the scrap-box R².

In the operation of the machine the paste 85 is received on the feeding-apron I from suitable preparing-rollers, and its front edge is carried forward rapidly to the cutters by the operator turning the handle i. (See lower section of Fig. 1.) When the machine is started 90 the cutter-block is forced up to the cutters as a part of the hinged reciprocating frame D', and the interposed paste is cut and the lozenges retained in the base of the cutters when the frame recedes. The succeeding strokes of the 95 cutter-block crowd the lozenges upward in the base of the cutters, and as they appear above the base they are series by series removed by the downwardly-projecting ends of the finger-bars G², and drawn within the reach of the 100 conveyer-bars. As the frame D' works up and down the paste is fed forward at proper intervals, so that the cutters strike clear of the perforations made on the previous stroke. The forward movement of the paste also carries the waste and deposits it upon the waste-conveyer R. The cut lozenges now being within the control of the conveyer-bars are carried to and operated upon in succession by the embossing-head and the printing-head, 110 and are finally deposited upon the receiving-trays in rows at regular intervals, ready for drying. The several operations necessary to prepare and finish the lozenge are timed to be in unison one with the other, and the construction of the machine is such that the whole work is entirely automatic, and is performed 115 with rapidity and accuracy.

I claim as my invention—

1. The pivoted frame D', carrying the cutter-block D and provided with rollers for carrying the apron I, in combination with the cutter-block D, apron I, stationary cutter-head E, cutters F, and means, substantially as described, for giving the pivoted frame a vertical movement at its outer end, as and for the purpose specified.

2. In combination with the tubular cutters F and the slotted shanks thereof, the hooks G², passing through said slotted shanks and connected to the reciprocating conveyer-bars, substantially as and for the purpose specified.

3. In a lozenge-machine, the conveyer-table G, provided with a series of ridges, G', in combination with the reciprocating finger-bars G², substantially as and for the purpose specified.

4. The combination of the channeled cam-wheels, the pivoted paste-frame, with cutter-block and intermittently-moving apron mounted thereon, and a stationary cutter-head, substantially as shown and described.

5. The combination of the channeled cam-wheels, the reciprocating frame carrying the

cutter-block and intermittently-moving apron, the cutter-head, the embossing and printing heads, and mechanism, substantially as described, for connecting and operating said parts, and the lozenge-conveying mechanism and receiving-trays, arranged and operating substantially as shown and described.

THOS. ROBERTSON.
